PACKING CASE FOR BOTTLES

Filed June 27, 1921

Patented Apr. 7, 1925.

1,532,448

UNITED STATES PATENT OFFICE.

WALTER G. SEABOLD, OF ALTON, ILLINOIS, ASSIGNEE TO ILLINOIS GLASS COMPANY,
OF ALTON, ILLINOIS, A CORPORATION OF ILLINOIS.

PACKING CASE FOR BOTTLES.

Application filed June 27, 1921. Serial No. 430,568.

To all whom it may concern:

Be it known that I, WALTER G. SEABOLD, a citizen of the United States of America, and a resident of Alton, in the county of 5 Madison and State of Illinois, have invented certain new and useful Improvements in Packing Cases for Bottles, of which the following is a full, clear, and exact description, reference being had to the accompanying 10 drawings, forming a part of this specification.

This invention relates to improvements in packing cases for bottles and has for its object the production of a simple and inexpensive packing case the use of which will 15 reduce to a minimum the danger of accidental breakage of the bottles contained therein.

In the invention disclosed herein a packing 20 case is provided which comprises an inner and an outer crate, each of which is provided with cushioning means whereby any shock, regardless of whether it is caused by the packing case falling upon one of its 25 sides, a corner, or its bottom will be transmitted through the cushioning means for the bottle contained in said crate.

Briefly stated my improved packing case 30 comprises an inner crate having comparatively heavy nonresilient corner members, and comparatively heavy nonresilient bottom supporting members. Narrow resilient cushion members having their opposite ends secured to the inside faces of adjacent corner members form resilient walls in said 35 inner crate, and resilient cushion members similar to those just mentioned have their opposite ends secured to the bottom supporting members whereby a resilient bottom 40 is formed in said receptacle. This inner crate, which is adapted to receive a bottle, may be placed within an outer crate comprising a comparatively heavy nonresilient upper marginal frame member and a comparatively heavy nonresilient lower marginal frame member. Resilient cushion 45 members, the opposite ends of which are secured to said upper and lower frame members, provide said outer crate with resilient walls. The outer crate is also provided with a bottom which is secured to the bottom face of the lower marginal frame member, and a hinged cover secured to the upper 50 marginal frame member.

With the foregoing and other objects in

view, the invention comprises the novel construction, combination and arrangement of parts hereinafter more specifically described and illustrated in the accompanying drawings wherein is shown the preferred embodiment of the invention. However, it is to be understood that the invention comprehends changes, variations and modifications which come within the scope of the claims hereunto appended. 60

Fig. I is a vertical section of my improved packing case showing a bottle in place therein.

Fig. II is a horizontal section through the packing case shown in Fig. I. 70

Fig. III is a perspective of the inner receptacle.

Fig. IV is a perspective of the outer receptacle.

In the drawings A designates an inner 75 receptacle in the form of a crate adapted to contain a bottle and comprising nonresilient vertical corner members 1, each corner member being formed of two comparatively thick strips of wood which are 80 nailed to each other to form an L-shaped post.

Secured to the corner posts 1, by means of 85 nails or other suitable means, whereby said corner posts are connected together, is a plurality of cushion members 2, in the form of comparatively thin resilient strips of wood. Each wall of the inner receptacle is thus formed of a pair of vertical corner posts 1 and a plurality of horizontal cushion 90 members 2.

Secured to the bottom face of adjacent corner posts 1 is a pair of comparatively thick oppositely disposed bottom supporting member 3, said bottom supporting members being adapted to support a receptacle bottom composed of a plurality of comparatively thin strips of wood 4 similar to the cushion members 2 which form part of the bottom wall of the receptacle A. 100

It will be noted by referring to the drawing that the cushion members 2 are secured in place by having their opposite ends fastened, by means of nails or similar fastening devices, to the inside faces of the corner posts 1, and that the bottom strips 4 have their opposite ends secured to the top face of the bottom supporting members 3. The corner posts 1 are arranged to form the corners of a square figure having equal 110

sides, and the yielding strips 2 form the sides of a smaller square figure. The periphery of the bottle contacts with the middle portions of the yielding strips 2 which are protected by the rigid corner posts. The importance of this feature lies in the fact that in the event the packing case is dropped on one of its sides, or on one of its corners, one or more of the corner posts may strike the object on to which said case is dropped, but because the yielding strips 2 against which the bottle bears are spaced from the outside face of the posts 1 said strips 2 will not strike the object on to which said case is dropped but will act as cushions to prevent breakage of the bottle.

To prevent accidental breaking of the bottle when the packing case is dropped or forcibly seated upon its bottom I provide a cushion seat 3 upon which the bottle rests, said cushion seat comprising a comparatively thick block 5 which is secured to one of the bottom strips 4 in any suitable manner, and a comparatively thin resilient strip of wood 6 which is secured at its center to said block 5, said resilient strip 6 being provided at its ends with a pair of bottle supporting blocks 7. It is apparent that if the packing case is dropped in such a manner that its bottom strikes the floor, the resilient strip 6 will act as a cushion to prevent breakage of the bottle.

For making local deliveries, the bottle may be transported in the inner crate alone, but in making shipments to a distant point, as for instance by railroad, this inner crate A is placed in an outer crate C which more completely incloses the bottle.

The outer crate C comprises a continuous horizontally disposed lower rectangular marginal frame member 8 formed of four comparatively thick pieces of wood, and a continuous upper rectangular marginal frame 9 similar to the lower marginal frame 8. A suitable bottom 10 is secured to the bottom face of the lower marginal frame member 8, and a cover 11 is hinged to the upper marginal frame member 9.

Vertical cushion strips 12 in the form of thin resilient strips of wood have their opposite ends located within and secured to the inside faces of the upper and lower marginal frames 8 and 9, so as to form the side walls of the outer crate.

When the inner crate A is located within the outer crate C as is shown in Figs. I and II, the corner posts 1 on the inner crate engage the vertical cushion strips 12 on the outer receptacle, and the cushion strips 2 on the inner receptacle are entirely separated from the outer receptacle so as to serve as yielding cushions for the bottle.

What has been said regarding the cushion members 2 of the inner crate A being

secured to the inside faces of the corner posts 1 to prevent said cushion members from striking the floor when the packing case is dropped, is likewise true of the cushion strips 12 which have their opposite ends secured to the inner faces of the lower and upper marginal frame members 8 and 9, whereby an additional cushioning means is provided to eliminate the danger of the bottle being broken.

When the inner and outer crates A and C are assembled as is shown in Figs. I and II the cushion members 12 of the outer crate are located adjacent to the skeleton walls of the inner receptacle formed by the cushion strips 2. The upright cushion members 12 are wider than the distance between the corner posts 1, so the bottle is almost entirely enclosed by the double crate.

Prior to this invention, bottle crates have been provided with various types of cushioning devices formed separate from the frames of the crates, but in the structure herein disclosed, the horizontal frame members 2 are secured to inner faces of the corner posts 1, so as to serve as cushions for the bottle. In a similar manner, the vertical connecting strips 12 of the outer crate are secured to inner faces of the rigid frames 8 and 9 to serve as shock absorbers for the bottle.

I claim:

1. A packing case for bottles comprising an inner crate having comparatively heavy non-resilient frame members, resilient cushion members secured to inner faces of said non-resilient frame members and adapted to contact with the periphery of the bottle, and an outer crate having comparatively heavy non-resilient marginal frame members, resilient cushion members secured to said non-resilient marginal frame members and engaged by the first mentioned non-resilient frame members, so as to provide cushions for the inner crate, a bottom secured to one of said marginal frame members, and a cover to close said outer crate.

2. A packing case for bottles comprising an inner crate having comparatively heavy upright non-resilient corner members, resilient cushion strips the opposite ends of which are secured to the inside faces of said non-resilient corner members to form cushions for the bottle, and an outer crate having comparatively heavy non-resilient marginal frames, resilient cushion strips engaging said corner members and having their opposite ends secured to the inside faces of said marginal frames, a receptacle bottom secured to one of the marginal frames, and a cover to close said outer crate.

3. A packing case for bottles comprising an inner crate having comparatively heavy non-resilient upright corner members, horizontal resilient cushion strips separated

from each other and extending from one of said corner members to another to form cushions for the bottle, the opposite ends of said resilient cushion strips being secured 5 to the inside faces of said corner members, a resilient bottom in said inner crate, and an outer crate having comparatively heavy non-resilient upper and lower rectangular marginal frames, upright resilient cushion strips of less width than said marginal frames, the opposite ends of said upright 10 resilient cushion strips being secured to the inside faces of said marginal frames, said

upright resilient cushion strips being in contact with said non-resilient upright corner members so as to form cushions for the inner 15 crate, the width of said upright cushion strips being greater than the distance between said upright corner members, a bottom secured to said lower marginal frame, 20 and a closure hinged to said upper marginal frame.

In testimony that I claim the foregoing I hereunto affix my signature.

WALTER G. SEABOLD.
